UNITED STATES PATENT OFFICE.

THOMAS W. VARLEY, OF NEW YORK, N. Y., ASSIGNOR TO WESTINGHOUSE ELECTRIC
AND MANUFACTURING COMPANY, A CORPORATION OF PENNSYLVANIA.

CURRENT-COLLECTING DEVICE.

1,267,342.

Specification of Letters Patent. Patented May 21, 1918.

Original application filed October 3, 1913, Serial No. 793,123, (now Patent No. 1,234,976, dated July 31, 1917.) Divided and application filed June 5, 1916, Serial No. 101,716. Divided and this application filed May 7, 1917. Serial No. 167,082.

To all whom it may concern:

Be it known that I, THOMAS W. VARLEY, a citizen of the United States, and a resident of New York, in the county of New York 5 and State of New York, have invented a new and useful Improvement in Current-Collecting Devices, this application being a division of application Serial No. 101,716, filed June 5, 1916, that is a division of application 10 Serial No. 793,123, filed October 3, 1913, which resulted in Patent No. 1,234,976, issued July 31, 1917.

My invention relates to current-collecting devices and particularly to brush devices 15 for motor-meters.

One object of my invention is to provide a current-collecting or brush device that shall have a visible means for indicating the relative pressure of its brushes or contact 20 members on the commutator cylinder.

Another object of my invention is to provide a current-collecting device of the above indicated character that shall be cheap to construct and effective in its operation.

It is desirable, in motor-meters of the commutator type, to maintain the brush pressure relatively low for the purpose of decreasing the energy loss that is caused by friction of the moving parts. In view of 25 this, it is desirable to observe the relative pressure of the brushes on the commutator cylinder, and, in order to observe this, I provide a relatively short stiff member that is adapted to be supported by the same member 30 that supports the brush and to be normally in alinement therewith. Thus, when the brush is pressed against the commutator cylinder, the angle between the relatively stiff member and the brush serves to indicate 35 the relative pressure of the brush on the commutator cylinder.

In the accompanying drawings, Figure 1 is a side view, partially in section and partially in elevation, of a portion of a motor-meter embodying my invention, Fig. 2 is a 45 top plan view of the brush device shown in Fig. 1 of the drawings, and Fig. 3 is a fragmentary view of the brush device illustrating the position of the elements under condition of tension.

The motor-meter 1 comprises, in general, a shaft 2 upon which are mounted an armature 3 and a commutator cylinder 4, and a

brush device 5 that is adapted to coöperate with the commutator cylinder.

The brush device 5 comprises two sets of brushes 6 and 7 that are mounted at the ends of resilient members 8 and 9 which are supported by pivotally-mounted blocks 10 and 11. The blocks 10 and 11 are mounted on a 55 plate member 12 and are adapted to be adjusted by means of thumb nuts 13 and 14 and screws 15 and 16 against the force of springs 17 and 18. Guide members 19 and 20, consisting of relatively short stiff metal 60 strips that are bent at their ends, are attached to the pivotally-mounted blocks 10 and 11, respectively, and are normally in direct alinement with the resilient supporting 65 members 8 and 9 of the respective brushes. 70

In order to determine the relative pressure of the brushes 6 and 7 on the commutator cylinder 4, it is only necessary to observe the angular relation between the guide members 19 and 20 and the respective resilient 75 supporting members 8 and 9. That is, if the brushes are not pressed against the commutator cylinder 4, the resilient members 8 and 9 will remain in direct alinement with their respective guide members. However, if the 80 blocks 10 and 11 are so turned, by adjusting the nuts 13 and 14, that excessive pressure is exerted on the commutator cylinder 4, the resilient members 8 and 9 will assume a somewhat bowed shape and the angular relation between the members 8 and 9 and the respective guide members 19 and 20 will be an indication of the relative pressure exerted on the commutator cylinder.

While I have shown my invention in its 90 preferred form, it will, of course, be understood that the changes in the size, the shape and the construction may be made without departing from the spirit and scope of the invention as set forth in the appended 95 claims.

I claim as my invention:

1. A current-collecting device comprising a brush, a relatively stiff member, and a supporting member adapted to support the said 100 brush and the said relatively stiff member normally in alinement, said relatively stiff member being relatively shorter than the brush.

2. A current-collecting device comprising 105 a flat resilient brush, a relatively stiff mem-

ber, and a supporting member adapted to so support the brush and the relatively stiff member that, when the brush is not tensioned, they will be substantially in alinement.

3. A current-collecting device comprising a flat resilient brush, a relatively short stiff member, and a supporting member for the brush and the stiff member, said stiff member being so disposed with respect to the brush that the relative tension of the brush may be observed by observing the relative position of the brush with respect to the stiff member.

4. In a motor, the combination with a commutator cylinder, of a brush having a relatively stiff member normally in alinement therewith and relatively shorter than the brush, and a single member for supporting the said brush and the said relatively stiff member.

5. A current-collecting device comprising a contact member, means for resiliently supporting the same, and a relatively short stiff member normally in alinement with the said resilient supporting means and adapted to indicate, by the difference in alinement, the pressure being exerted by the contact member.

6. A current-collecting device comprising a resiliently-mounted contact member, a relatively short stiff member normally in alinement with the contact member, and a single means for supporting the said members, said short stiff member being adapted to indicate, by the difference in alinement with the contact member, the relative pressure being exerted by the contact member.

In testimony whereof, I have hereunto subscribed my name this 2nd day of May 40, 1917.

THOMAS W. VARLEY.
